WPCarr

ATTORNEY

UNITED STATES PATENT OFFICE

118,852

DESIGN FOR AN AIR COMPRESSING UNIT

Franklin D. Ditch, Toledo, Ohio, assignor to The
De Vilbiss Company, Toledo, Ohio, a corpora-
tion of Ohio

Application August 3, 1939, Serial No. 86,433

Term of patent 7 years

To all whom it may concern:

Be it known that I, Franklin D. Ditch, a citizen of the United States and resident of Toledo, in the county of Lucas and State of Ohio, have invented a new, original, and ornamental Design for an Air Compressing Unit, of which the following is a specification, reference being had to the accompanying drawing, forming a part thereof.

In the drawing, Figure 1 is a perspective view of an air compressing unit showing my new design; and Figure 2 is a similar perspective view

of the same air compressing unit turned slightly to the left.

The side of the compressing unit opposite to that shown in the drawing is identical thereto in appearance except that the opposite side does not have the air strainer on the compressor nor the small drain valve on the air tank between the compressor and the motor.

I claim:

The ornamental design for an air compressing unit, substantially as shown and described.

FRANKLIN D. DITCH.
